(57) **ABSTRACT**

A high caliber target includes a target plate and a stand. The target plate may be mounted on and removed from the stand. In accordance with one embodiment, the target plate can be mounted and removed without tools. In accordance with one embodiment, the target plate is presented to the shooter without joints or edges which could promote ricochets back toward the shooter. In accordance with another embodiment, the target plate can pivot on impact relative to the stand.

HIGH CALIBER TARGET

THE FIELD OF THE INVENTION

The present invention relates to targets used for target practice. More specifically, the present invention relates to a target which can withstand high caliber rounds and which may be portable.

BACKGROUND

In order to maintain proficiency in the use of firearms, it is common for law enforcement officers, members of the military and sportsmen to engage in target practice. While many perceive target practice as simply a method for improving accuracy, it is important for law enforcement officers, members of the military and the like to conduct target practice in scenarios which improve timing and the ability to make split-second decisions on whether or not to fire. Such split-second decisions can mean the difference between life and death both for the officer or soldier and those around them. For example, a police officer who fires too quickly may shoot an unarmed person. If he or she delays too long, however, a perpetrator may shoot a bystander.

In the military context a sniper must often make a split second decision on whether to fire at a target. The person could be an enemy combatant holding a rocket-propelled grenade or simply a person carrying a pipe. To simulate different scenarios, it is often desirable to move one or more targets around. For example, target one may be an enemy combatant, and targets two and three are innocent civilians. Training is often improved by subjecting the shooter numerous different scenarios to prevent expectancy of the proper response.

While there are a wide variety of targets which are useful with smaller caliber rounds, such as a 0.223 or similar round, there are a more limited number of targets which are useful with high caliber rounds when a much larger projectile is fired into the target. For example, some machine guns and many sniper rifles fire a .50 BMG round (12.7x99 mm NATO), in which the weight of the projectile is typically about 620-710 grains (40-46 grams). Thus, the weight of the projectile used in these high caliber rounds can easily be 10 times that of the common infantry rifle.

Stopping a .50 BMG round presents a challenge at shooting ranges, especially where the targets are desired to be mobile. Most targets which will handle more common rounds, such as 30-06 and below, can be damaged by higher caliber rounds such as the .50 BMG. Thus, either the target is damaged by the impact of the projectile, or the target is so large and bulky as to be difficult to move.

While attempts at portable targets that will withstand .50 BMG rounds have been made, some are prone to falling over when impacted by the projectile. Others leave exposed hardware or joints or edges which can create a ricochet risk which is of particular concern with such a high powered round.

Thus there is a need for an improved target which can be used with high caliber rounds with little or no damage, provides little risk of ricochet, and remains transportable about a shooting range, etc.

SUMMARY OF THE INVENTION

Embodiments of an improved target and associated methods are disclosed below. According to some configurations,

2

the target system includes a target plate having a mounting bracket system attached thereto, and a stand which engages the mounting bracket to hold the target plate in position during use.

In accordance with one aspect of the disclosure, the mounting bracket system attached to the target plate may be provided with a first mount in the form of a mounting bracket and a second mount in the form of a second mounting bracket. While both the first mounting bracket and the second mounting bracket may engage the stand, the second mounting bracket engages the stand in such a manner that the mounting bracket may slide forwardly and rearwardly with respect to the stand. Thus, when the target plate is impacted by a high caliber projectile, the target plate can pivot with respect to the stand so that a portion of the kinetic energy of the projectile is consumed in pivoting the target plate upon impact.

In accordance with another aspect of the invention, the target stand engages the mounting brackets at at least two spaced apart locations. The spaced apart engagement helps to prevent the target plate from being turned sideways when impacted by the projectile.

In accordance with another aspect of the invention, the mounting brackets attached to the target plate are configured to slide onto and off of the stand without the need for any tools to thereby allow for tool-less mounting and removal of the target plate on the stand. This, in turn, facilitates the target being disassembled, moved and reassembled without the need for tools.

It will be appreciated that the present invention provides various aspects and different embodiments provide different advantages. Thus, it will be appreciated that each embodiment need not provide all aspects or advantages of the present invention while still falling within the general scope of the invention as set forth in the appended claims.

BRIEF DESCRIPTION OF THE DRAWINGS

Various embodiments and features of target systems are shown and described in reference to the following numbered drawings:

FIG. 1 shows a front view of an exemplary embodiment of a high caliber target made in accordance with principles of the present disclosure;

FIG. 2 shows a side view of the high caliber target of FIG. 1;

FIG. 3 shows a partially exploded view of the high caliber target shown in FIG. 1;

FIG. 4 shows a close-up view of the target plate and mounting bracket system; and

FIG. 5 shows an exploded view of the stand on which the target plate is mounted.

It will be appreciated that the drawings are illustrative and not limiting of the scope of the invention which is defined by the appended claims. The embodiments shown accomplish various aspects of the invention. It is appreciated that it is not possible to clearly show each element and aspect of an invention in a single figure, and as such, multiple figures are presented to separately illustrate the various details of embodiments of target systems in greater clarity. Several aspects from different figures may be used in accordance with target systems in a single structure. Similarly, not every embodiment need accomplish all advantages of various embodiments of target systems.

DETAILED DESCRIPTION

The invention and accompanying drawings will now be discussed in reference to the numerals provided therein so as

to enable one skilled in the art to practice the present invention. The skilled artisan will understand, however, that the apparatuses, systems and methods described below can be practiced without employing these specific details, or that they can be used for purposes other than those described herein. Indeed, they can be modified and can be used in conjunction with products and techniques known to those of skill in the art in light of the present disclosure. The drawings and descriptions are intended to be exemplary of various aspects of the invention and are not intended to narrow the scope of the appended claims. Furthermore, it will be appreciated that the drawings may show aspects of the invention in isolation and the elements in one figure may be used in conjunction with elements shown in other figures.

Reference in the specification to "one configuration" "one embodiment," "a configuration" or "an embodiment" means that a particular feature, structure, or characteristic described in connection with the configuration is included in at least one configuration, but is not a requirement that such feature, structure or characteristic be present in any particular configuration unless expressly set forth in the claims as being present. The appearances of the phrase "in one configuration" in various places may not necessarily limit the inclusion of a particular element of the invention to a single configuration, rather the element may be included in other or all configurations discussed herein.

Furthermore, the described features, structures, or characteristics of configurations of the invention may be combined in any suitable manner in one or more configurations. In the following description, numerous specific details are provided, such as examples of products or manufacturing techniques that may be used, to provide a thorough understanding of configurations of the invention. One skilled in the relevant art will recognize, however, that configurations of the invention may be practiced without one or more of the specific details, or with other methods, components, materials, and so forth. In other instances, well-known structures, materials, or operations are not shown or described in detail to avoid obscuring aspects of the invention.

Before the present invention is disclosed and described in detail, it should be understood that the present disclosure is not limited to any particular structures, process steps, or materials discussed or disclosed herein, but is extended to include equivalents thereof as would be recognized by those of ordinarily skill in the relevant art. More specifically, the invention is defined by the terms set forth in the claims. It should also be understood that terminology contained herein is used for the purpose of describing particular aspects of the invention only and is not intended to limit the invention to the aspects or configurations shown unless expressly indicated as such. Likewise, the discussion of any particular aspect of the invention is not to be understood as a requirement that such aspect is required to be present apart from an express inclusion of the aspect in the claims.

It should also be noted that, as used in this specification and the appended claims, singular forms such as "a," "an," and "the" may include the plural unless the context clearly dictates otherwise. Thus, for example, reference to "a channel" may include one or more of such channels, and reference to "the backing" may include reference to one or more of such backings.

As used herein, the term "substantially" refers to the complete or nearly complete extent or degree of an action, characteristic, property, state, structure, item, or result to function as indicated. For example, an object, such as tubing, that is "substantially" enclosed would mean that the object is either completely enclosed or nearly completely

enclosed. The exact allowable degree of deviation from absolute completeness may in some cases depend on the specific context, such that enclosing nearly all of the length of a piece of tubing would be substantially enclosed, even if the distal end of the structure enclosing the tubing had a slit or channel formed along a portion thereof. The use of "substantially" is equally applicable when used in a negative connotation to refer to the complete or near complete lack of an action, characteristic, property, state, structure, item, or result. For example, structure which is "substantially free of" a bottom would either completely lack a bottom or so nearly completely lack a bottom that the effect would be effectively the same as if it lacked a bottom.

As used herein, the term "about" is used to provide flexibility to a numerical range endpoint by providing that a given value may be "a little above" or "a little below" the endpoint while still accomplishing the function associated with the range.

As used herein, a plurality of items, structural elements, compositional elements, and/or materials may be presented in a common list for convenience. However, these lists should be construed as though each member of the list is individually identified as a separate and unique member.

Concentrations, amounts, proportions and other numerical data may be expressed or presented herein in a range format. It is to be understood that such a range format is used merely for convenience and brevity and thus should be interpreted flexibly to include not only the numerical values explicitly recited as the limits of the range, but also to include all the individual numerical values or sub-ranges encompassed within that range as if each numerical value and sub-range is explicitly recited. As an illustration, a numerical range of "about 1 to about 5" should be interpreted to include not only the explicitly recited values of about 1 to about 5, but also include individual values and sub-ranges within the indicated range. Thus, included in this numerical range are individual values such as 2, 3, and 4 and sub-ranges such as from 1-3, from 2-4, and from 3-5, etc., as well as 1, 2, 3, 4, and 5, individually. This same principle applies to ranges reciting only one numerical value as a minimum or a maximum. Furthermore, such an interpretation should apply regardless of the breadth of the range or the characteristics being described.

Turning now to FIG. 1 there is shown a front view of an exemplary embodiment of a high caliber target, generally indicated at 10, made in accordance with principles of the present invention. The high caliber target 10 includes a target plate 14 and a stand 18. The target plate 14 will typically be made from hardened steel, such as AR500 or AR550, having a thickness of $\frac{3}{8}$ " of an inch or greater. It will be appreciated that while soft steel could be used, it would quickly be damaged by the high velocity projectiles and a thicker piece would need to be used.

The target plate 14 may be of any desired shape. For example, in FIG. 1 the target plate 14 has the general shape of an FBI-Q silhouette training target. Other common shapes may include a FBI-QIT-G, a B-27, a Dunbar Armored Qualification Target, etc., or other shapes which resemble likely targets. If desired, markings could be painted on or otherwise applied to the target plate 14. (It will be appreciated that a .50 BMG round is used both by snipers to hit targets more than a mile away and to disable vehicles and the like).

The stand 18 is designed to hold the target plate 14 at a desired height. Additionally the target stand 18 includes two supports 22, the supports comprising mounting arms or mounting structures 34, which engage the target plate 14 to

help minimize torsional movement when the impact of a projectile occurs to either side of the center of the plate. In some configurations, the target stand **18** may include one support **22** or mounting structure. The target stand **18** also includes a number of feet **26** which extend outwardly from the supports **22** to provide support and prevent the target plate **14** and target stand **18** from tipping over.

Turning now to FIG. 2, there is shown a side view of the high caliber portable target **10**. As shown, the stand **18** is configured to hold the target plate **14** at an angle relative to vertical. The target plate **14** is typically held at an angle between 5 and 45 degrees, commonly between 10 and 25 degrees and most commonly at between about 15 and 20 degrees. The angle of the target plate **14** helps to deflect bullets downwardly after they have impacted the target plate **14** to thereby prevent ricochets back toward the shooter. It will be appreciated that the greater the angle relative to the vertical, the easier it is for the target to deflect the energy of a projectile without damaging the target.

Mounting brackets **30** are attached to the back of the target plate **14** and receive one or more mounting arms or other mounting structures **34** of the stand **18**. The mounting arms or mounting structures **34** may be attached to the upper end of the supports **22** of the stand **18**, or the mounting structures **34** may be formed integrally to the supports **22**. In accordance with one aspect of the invention, the mounting brackets **30** engage the mounting structures **34** in a manner that the mounting brackets **30** can be placed on and removed from the mounting structures **34** without the use of tools. This may be desirable when one desires to move the high caliber portable target **10** from one position to another. A target plate **14** made of AR550 hardened steel which is 18" by 40" and shaped as shown in FIG. 1 will weigh just about 100 pounds with the brackets and targets attached. Thus, to move the target **10**, the target plate **14** may be removed, the stand **18** moved to the new designed location and then the target plate **14** remounted on the mounting structures **34** of the stand **18**. A single person can relocate the stand **18** if necessary.

Turning now to FIG. 3, there is shown a partially exploded view of the high caliber portable target **10**. The target plate **14** has been removed from the stand **18** to better show the engagement between the two structures. As was mentioned previously, the target plate **14** may have two or more mounting brackets **30** attached thereto. The mounting brackets **30** are designed to engage the stand **18**. In one preferred embodiment this is done so that the mounting brackets **30** can be mounted on the stand **18** and removed therefrom without the use of tools.

Each of the mounting brackets **30** may include projections **30a** with slots **40** which receive the mounting arms or structures **34** of the stand **18**. In accordance with one aspect of some embodiments of the invention, the slots **40** on one of the mounting brackets **30** may be larger than the slots on the other mounting bracket. For example, as shown in FIG. 3 (and most visible in FIG. 4), the slots **40** on the upper mounting bracket are longer than the slots on the lower mounting bracket. When the mounting brackets **30** are mounted on the mounting arms **34** of the stand **18**, the larger slots **40** in the upper mounting bracket will allow the upper mounting bracket to slide relative to the mounting arms **34**. This effectively allows the target plate **14** to pivot with respect to stand **18** when impacted by a bullet. The amount of deflection allowed will be determined by the length of the slot **40** and the size of the mounting structure **34**. For example, the slot **40** may be sufficiently long relative to the

mounting structure **34** to allow the mounting bracket to slide so that the target plate **14** pivots between around 5 to 15 degrees.

Because of the weight of the target plate **14**, pivoting of the plate **14** dissipates energy. The amount of energy consumed reduces the amount of energy which the stand **18** must withstand without tipping over. Thus, the likelihood that the high caliber portable target **10** will tip over when impacted is reduced because of the energy dissipated by pivoting of the target plate **14**. Additionally, as can be seen in FIG. 2, the length of the feet **26** of the stand **18** is relatively large to provide additional support. Also shown in FIG. 2, the curved nature of the stand **18** helps to align the engagement between the mounting brackets **30** and mounting structures **34** above the engagement of the supports **22** with the feet **26**. The feet **26** may be formed on each side by one bent piece **26a** which is attached to the supports **22** of the stand **18** by bolts **44**, and one straight piece **26b** which is held to the supports by the same bolts. It will be appreciated that a similar configuration could be formed with a single piece forming the straight and bent portion, or with more than two pieces. The supports **22** may also be secured by a cross-support **50** attached to the supports by bolts **54**.

Turning now to FIG. 4, there is shown a close-up view of the target plate **14** and the mount formed thereon by mounting brackets **30** and their associated structures. The mounting brackets **30** may be welded (as represented at **58**) to the target plate **14**. As was discussed previously, the size of the slots **40a** in one mounting bracket **30** may be larger than the size of the slots **40b** in the other mounting bracket. This may be used to allow the target plate **14** to pivot. It will also be appreciated that other engagement arrangements could be used to allow the target plate **14** to pivot with respect to the stand when impacted by a bullet. For example, the slots **40** formed in the mounting brackets **30** could be the same size and the mounting structures **34** (FIG. 2) could be tapered or otherwise shaped to allow movement of one mounting bracket relative to the mounting structure while the other mounting bracket remains relatively still or moves to a lesser degree.

FIG. 4 also shows a pair of nuts **64** and bolts **68**. The bolts **68** pass through openings **60** in the mounting brackets. When the nuts **64** are tightened on the bolts **68**, the nuts and bolts help provide handles for gripping and moving the target plate **14**. Washers **70** may also be used with the nuts **64** and bolts **68** if desired.

Turning now to FIG. 5, there is shown an exploded view of the stand **18**. The stand **18** may be formed from a single support structure. However, the configuration shown in FIG. 5 may be advantageous for several reasons. First, the supports **22** are spaced apart by the cross-members **50** (two of which are shown in FIG. 5). The spacing of the supports **22** causes the mounting structures **34** to engage the mounting brackets **30** (FIGS. 2-4) a desirable distance from a center vertical plane. This helps to reduce torsion or turning of the target **10** when hit by a high velocity round at a position away from the center vertical plane. This is further enhanced by the rearward and outward spreading of the feet **26a** and **26b** which are attached near the bottom of the supports.

One advantage of the present configuration is that a pair of nuts and bolts **44** can be used to attach two different feet to the support **22** and to attach the cross-member **50** to the support, thereby reducing cost and materials. By simply removing four bolts the feet **26a**, **26b**, the cross-member **50** can be removed from the supports **22**. Removing another four nuts and bolts **54** allows the other cross-member **50** to be removed. Thus, a sturdy stand can be formed from a

relatively small amount of plate steel and bolts, and the stand can be readily disassembled for storage if the stand is not needed, or for transport if the target **10** is to be taken to a different location.

It will be appreciated that the stand **18** is likely to be hit occasionally by high velocity rounds which miss the target plate **14** (FIGS. 1-4). As shown, the stand can be formed from a relatively small amount of plate steel which will stand up to considerable impact from projectiles. The construction of the stand **18**, however, also leaves a relatively small amount of profile which a bullet could strike and cause an undesirable ricochet. For example, in some high caliber targets, the stand engages the target plate in such a manner that joints or edges are left exposed which could cause a bullet to ricochet back toward the shooter. In the configuration shown herein, there is no joint or edge along the front of target plate **14** which could cause such a ricochet. Additionally, the stand is configured to provide minimal risk of ricochet in the event that the shooter misses the target plate **14** altogether and hits the stand **18** instead.

Thus there is disclosed a high caliber portable target. It will be appreciated that numerous changes may be made to the above-disclosed embodiments of target systems and associated methods without departing from the scope of the claims. The appended claims are intended to cover such modifications.

What is claimed is:

1. A high caliber target comprising:
a target plate having an upper portion and a lower portion
and at least one mount disposed thereon, the at least one
mount having a slot formed therein; and
a stand for engaging the at least one mount to hold the
target plate in a desired position, the stand being
slidable into and out of the at least one mount to thereby
allow mounting and removal of the target plate from the
stand without tools, and wherein the slot formed in the
at least one mount is longer than a width of the stand
as it passes through the slot to allow the mount to slide
rearwardly relative to the stand when the target plate is
impacted by a projectile, the slot being sized relative to
the stand such that the upper portion of the target plate
may be deflected toward the stand when impacted by a
bullet and such that the lower portion of the target plate
does not pivot toward the stand.

2. The high caliber target of claim **1**, wherein the at least one mount comprises a mounting bracket having at least one slot formed therein and wherein the stand has at least one mounting arm insertable into and through the at least one slot, the at least one mounting arm having a width and the at least one slot being longer than the width of the at least one mounting arm to enable the at least one mounting arm to slide relative to the at least one slot when the target plate is impacted by a bullet and thereby pivot the target plate about a horizontal axis of rotation.

3. The high caliber target of claim **1**, wherein the stand includes at least one mounting arm and wherein the at least one mount comprises a first mounting bracket and a second mounting bracket, each of the mounting brackets having two slots formed therein, one slot from the first mounting bracket and one slot from the second mounting bracket being in alignment such that the at least one mounting arm passes through both slots.

4. The high caliber target of claim **3**, wherein the at least one mounting arm comprises two mounting arms, each of the mounting arms being extendable through one slot from the first mounting bracket and one slot from the second mounting bracket.

5. The high caliber target of claim **4**, wherein the slots in the second mounting bracket are larger than the slots in the first mounting bracket to enable the second mounting bracket to slide rearwardly along the two mounting arms when the target plate is hit by a bullet.

6. The high caliber target of claim **4**, wherein the two mounting arms are tapered to allow the at least one mounting bracket to slide along the two mounting arms when the target plate is hit by a bullet.

7. The high caliber target of claim **1**, wherein the target plate has an upper portion and a lower portion and wherein the target plate is pivotably mounted on the stand such that the lower portion of the target plate pivots toward the stand about a horizontal axis when impacted by a bullet.

8. The high caliber target of claim **7**, wherein the slot in the at least one mount and the stand are sized and slidable relative to each other to limit pivoting of the target plate to between 5 and 15 degrees when impacted by a bullet.

9. The high caliber target of claim **1**, wherein the at least one mount comprises a first mount and a second mount attached to the target plate, the first mount having a first slot and a second slot and the second mount having a first slot and a second slot, and wherein the stand has a first arm and a second arm, each of the arms having a width, and wherein the first slot and the second slot in the first mount are longer than the width of the first arm and the second arm so as to enable the first mount to slide back and forth on the arm.

10. The high caliber target of claim **9**, wherein the first mount and the second mount engage the first arm and the second arm of the stand to hold the target plate at an angle between 5 and 45 degrees less than vertical.

11. The high caliber target of claim **10**, wherein first arm and the second arm engage the first mount and the second mount to hold the target plate at an angle between 10 degrees and 25 degrees less than vertical.

12. A high caliber portable target comprising:
a target plate having a first mounting bracket and a second
mounting bracket attached thereto, each of the first
mounting bracket and the second mounting bracket
having at least one slot formed therein, the at least one
slot in the first mounting bracket being larger than the
at least one slot in the second mounting bracket; and
a stand having at least one mounting structure, the at least
one mounting structure extending through the at least
one slot in the first mounting bracket and the at least
one slot in the second mounting bracket to attach the
target plate to the stand, wherein the target plate is held
at an angle between 5 and 45 degrees less than vertical,
and wherein the slots are sized such that a lower portion
of the target can deflect when impacted by a projectile.

13. The high caliber portable target of claim **12**, wherein
the first mounting bracket has a plurality of slots and
wherein the second mounting bracket has a plurality of slots
and wherein the mounting structure of the stand extends
through the plurality of the slot in the first mounting bracket
and through the plurality of slots in the second mounting
bracket.

14. The high caliber portable target of claim **13**, wherein
the plurality of slots in the second mounting bracket are
larger than the plurality of slots in the first mounting bracket.

15. The high caliber portable target of claim **12**, wherein
the first mounting bracket and the second mounting bracket
are welded to the target plate.

16. The high caliber portable target of claim **12**, wherein
the target plate has opposing lateral sides, and wherein the
stand includes a first support having a mounting structure at
an upper end thereof, and a second support having a mount-

ing structure at an upper end thereof, the first support and the second support being spaced apart from each other so as to be positioned adjacent the opposing lateral sides of the target plate.

17. The high caliber portable target of claim 16, further comprising a plurality of cross-members attaching the first support to the second support. 5

18. The high caliber portable target of claim 12, wherein the at least one slot in the first mounting bracket and the at least one slot in the second mounting bracket engage the stand to hold the target plate at an angle of between 15 and 20 degrees less than vertical. 10

19. A kit for a high caliber target, the kit comprising:
a target plate having a first mounting bracket and a second
mounting bracket attached thereto; and 15
a stand comprising at least one mounting structure, the
mounting structure configured to extend through the
first mounting bracket and the second mounting bracket
to attach the target plate to the stand,
wherein the first mounting bracket has slots formed 20
therein and where the stand is slideable within the slots
so as to allow the target plate to pivot when impacted
by a bullet.

20. The kit according to claim 19, wherein the stand comprises a first support and a second support, and wherein 25
the kit further includes one or more cross-members configured to connect the first support to the second support.

21. The kit for a high caliber target of 19, wherein the second mounting bracket has slots formed therein and wherein the slots in the first mounting bracket are larger than 30
the slots in the second mounting bracket.
